UNITED STATES PATENT OFFICE

CHARLES ALFRED HUGHES AND EDWARD JOSEPH THOLE, OF EVANSVILLE, INDIANA

DESIGN FOR A BURGLARPROOF WINDOW GUARD

Application filed February 27, 1930. Serial No. 34,676. Term of patent 14 years.

To all whom it may concern:

Be it known that we, CHARLES ALFRED HUGHES and EDWARD JOSEPH THOLE, citizens of the United States, residing at Evansville, in the county of Vanderburgh and State of Indiana, have invented a new, original, and ornamental Design for Burglarproof Window Guard, of which the following is a specification, reference being had to the accompanying drawings, forming a part thereof, showing our design, in which:

Fig. 2 is a plan view.

We claim:

The ornamental design for a burglarproof window guard, as shown.

In testimony whereof we affix our signatures.

CHARLES ALFRED HUGHES.
EDWARD JOSEPH THOLE.
